Continuation of application Ser. No. 160,540, Dec. 19, 1961. This application July 8, 1965, Ser. No. 473,898
 3 Claims. (Cl. 178—5.4)

This is a continuation of my copending application Serial No. 160,540, filed December 19, 1961; now this invention concerns improvements of the color television receivers described in U.S. Patent No. 2,990,449, and in which are superimposed, upon a projection screen (EP), a detailed black-and-white picture of the televised scene produced by a first projector (Pbn), and a coarse picture of said scene, in saturated colors, produced by a second projector (Pc), a "luminance weighting device" (DPL) adjusting the ratio of white light (F₁) emerging from said first projector, to colored light (F₂) emerging from said second projector, in order to obtain the proper degree of color saturation for each point of the picture so produced on said screen (EP).

FIGURE 1-a represents the spectrum of the received videosignal (SV) applied to the receiver's videopart (PR) (FIGURE 1), L being the luminance signal, and (Chr) the chrominance signal from which are derived: (1) by means of an electronic circuit, not shown, the saturation signal (S) proportional to the degree of saturation of the color to be reproduced on projection screen (EP), and (2) by means of another electronic circuit (ME), a group (C) of 3 color signals corresponding to the blue, green and red components of the hue of said color to be reproduced.

(SVS) is the synchro-video-separator producing the field-synchronizing-signals (t₁) and the line-synchronizing-pulses (t₁).

In U.S. Patent No. 2,990,449, the "luminance weighting device" is a simple pentode, the control grid of which is energized by band (B₃) of the luminance spectrum (FIGURE 1-a), and is negatively biased by the saturation signal (S); the output voltage of said pentode is, in a mixer, added to band (B₂) of the luminance spectrum, and the output voltage (L') of said mixer is the "weighted luminance signal" controlling said first projector (Pbn) for producing a detailed black-and-white picture of the televised scene. In case of a large part of said scene having a uniform very saturated color, but having different brightnesses at different points, said mixer throws some white light upon the corresponding part of projection screen (EP), and therefore a uniformly very saturated color is not obtained as desired.

In the present invention, an improved "luminance weighting device (DPL)," constructed as shown on FIGURE 2, or on FIGURE 3, is controlled by the saturation signal (S) and by the whole luminance signal (L), that is the sum of band (B₃) and band (B₂) of FIGURE 1-a; the luminance weighted signal (L') produced at the output of said device (DPL) for controlling said first projector (Pbn) is exactly proportional to the ratio (L/S) of luminance to color saturation, and is practically zero in case of a part of the televised scene having a high degree of color saturation.

In U.S. Patent No. 2,990,449 the color-projector (Pc, FIGURE 1) comprises only one group of three juxtaposed crystals inserted between crossed polariser and analyser and respectively associated with color filters passing only a blue, or a green, or a red light; the birefractions of said crystals are respectively controlled by said 3 color signals (C, FIGURE 1) which correspond to the components of the hue of the color to be reproduced on screen (EP); so is produced a single thin beam of colored light, reflected successively on the mirrors of a rotating drum

2

(not shown on FIGURE 1) in order to sweep, at great speed, the entire surface of screen (EP); as said single thin beam of colored light moves at great speed, an adequate brightness is obtained, for the coarse picture of the televised scene in saturated colors, only if said screen has a small size.

In the present invention, the color projector (Pc) comprises as many groups of three juxtaposed crystals as there are colored elements in one line of the televised scene, and the corresponding thin beams of colored lights produce, on the projection screen (EP), juxtaposed colored elements which remain during the scanning time of said line of the televised scene, because an electronic memory device keeps constant, during that time, the controlling voltages applied to said crystals.

The invention will be better understood in referring to the appended drawings in which:

FIGURE 1 illustrates the principle of color television projection, and FIGURE 1-a shows the spectrum of the received videosignal;

FIGURES 2 and 3 are related to the improved luminance weighting device; FIGURES 4 and 4a illustrate a part of FIGURE 3;

FIGURES 5a and 5b are related to the optical arrangement of the color television receiver, and show a row of groups of three juxtaposed birefracting crystals, one group of three crystals being provided for each colored picture element of one line of the televised scene;

FIGURE 5 represents the "control chain" of one of these groups of three crystals, and shows the ferrite discs acting as electronic memory; FIGURES 5c and 5d illustrate part of FIGURE 5.

Referring now to FIGURE 2, which represents one mode of construction of the luminance weighting device (DPL) of FIGURE 1, the electric filter F separates the luminance signal (L)—bands (B₃) and (B₂) of the spectrum of the received videosignal (SV) shown on FIGURE 1-a; said signal (L) is applied to the input terminal of an amplifier having a high gain (A), and made of pentodes (V₁) and (V₂) and cathode-follower (V₃); said amplifier is stabilized by a voltage-feed-back-circuit (resistor r₁), the current-feed-back being negligible because resistor (r₂) is small compared to resistor (r₃).

V₄ is an heptode having its first control grid (g₁) energized by the output voltage Z of cathode follower V₃, its second control grid (g₃) energized by the saturation signal S, and its cathode c connected to ground; suitable bias (p₁, p₂, p₃) are applied to said control grids (g₁, g₃) and to the screen-grids (g₂, g₄). On the anode of heptode V₄ is obtained a voltage (—k.Z.S), k being a constant, which is applied to the control-grid (g) of pentode V₁, simultaneously with luminance signal L.

Consequently, Z=A (L—k.Z.S) and, as A is very great,

$$Z = \frac{1}{k} \frac{L}{S}$$

Z is therefore the desired weighted luminance signal (called L' on FIGURE 1) for controlling the black and white television projector (Pbn).

FIGURE 3 represents another mode of construction of the luminance weighting device (DPL) of FIGURE 1; F is again an electric filter energized by the received video signal SV and separating the luminance signal L applied to the high gain amplifier A_m (made of pentodes V₁ V₂ and cathode follower V₃ of FIGURE 2). The output voltage Z of A_m and the saturation signal S are simultaneously applied to electronic added (Add) producing, at its output, an electric voltage (Z+S), and to electronic subtractor (Sou) producing, at its output, an electric voltage (Z—S). R₁ and R₂ are non-linear-amplifiers

producing, at their output terminals, voltages equal to the square of the input voltages; the output voltages of R_1 and R_2 , equal respectively to $(Z+S)^2$ and $(Z-S)^2$, are simultaneously applied to electronic subtracter (Sou'), which produces a voltage equal to:

$$(Z-S)^2 - (Z+S)^2 = Z^2 - 2ZS + S^2 - (Z^2 + 2ZS + S^2) = -4ZS$$

This electric voltage $(-4ZS)$ is applied to the input of amplifier A_m (having a high gain A), simultaneously with luminance signal L . Consequently:

$$Z = A(L - 4ZS)$$

and, as A is very great,

$$Z = \frac{1}{4} L$$

Z is therefore the desired luminance weighted signal (called L' on FIGURE 1) for controlling the black and white television projector (P_{bn}).

FIGURE 4 illustrates the operation of the non-linear amplifiers R_1 , R_2 of FIGURE 2. When the voltage T_1 applied to the grid of the double cathode-follower V increases, the diodes (D_1 , D_2 , D_3 , D_4) in the output circuit conduct, so that the output resistance (made of resistor R and said diodes) decreases progressively, and the rate of increase of the output voltage T_2 increases correspondingly; FIGURE 4a represents the transfer characteristic so obtained: dotted polygon, within the solid curve of equation $T_2 = (T_1)^2$, and having as many linear parts as diodes inserted in the output circuit of FIGURE 4.

Referring to FIGURE 5a, which represents the optical arrangement of the color projector (P_c , FIGURE 1) for producing said coarse picture, in saturated colors, of the televised scene: each thin beam of white light emitted by a source (σ_p) and collimated by a lens l_{1p} is color-modulated by a group of three juxtaposed transparent ferroelectric bodies (k_{bp} , k_{vp} , k_{rp}) associated with color filters (f_{bp} for blue, f_{vp} for green, and f_{rp} for red), P being a polariser and A an analyser crossed with P .

The colored light emerging from lens l_{2p} is, after reflection on rotating mirror drum M_t , concentrated on a small elemental area of projection screen EP for producing the pth element of one line of the coarse colored picture of the televised scene. In accordance with the American color television standards (60 interlaced fields per second, aspect ratio 4/3), assuming a chrominance signal occupying a bandwidth of 1 megacycle per second, there will be 188 groups of 3 transparent bodies (such as k_{bp} , k_{vp} , k_{rp} on FIGURE 5b) aligned on a common electrode P_1 .

The ferroelectric transparent bodies (such as k_{bp} , k_{vp} , k_{rp} of FIGURES 5 and 5a) are, for example, small cubic monocrystals of barium titanate ($BaTiO_3$) cut perpendicularly to their optic axis; wires b_p , v_p , r_p (FIG. 5b) apply to said crystals the hue signals (B for blue, V for green and R for red) derived from the received video-signal SV (FIGURE 5). In this case use is made of the transversal effect, the luminous rays being perpendicular to the plane of FIGURE 5b whereas the modulating voltage (applied by wires b_p , v_p or r_p and producing the desired birefraction) is parallel to said plane. For such cubes of barium titanate monocrystal, the voltage required, between P_1 and b_p (or v_p , or r_p), for producing the maximum light intensity change is of the order of 400 volts.

For increasing the brightness of the colored picture produced on screen EP (FIGURE 5a), memories are inserted in the control chain of the electric birefraction of transparent bodies k_{bp} , k_{vp} , k_{rp} ; these memories are, for example, the ferrite disks D_{bp} , D_{vp} , D_{rp} (associated with D_{1p}) shown on FIGURE 5; they maintain the light for each element of the colored picture on screen EP

during the duration (T) of one scanning line as explained hereafter.

FIGURE 5c, on the left shows one of these ferrite discs (D) with 3 openings, offering 4 branches of equal width, respectively numbered 1, 2, 3 and 4.

In the hole between branches 1 and 2 pass: (1) a winding carrying a negative bias (CC) (shown on the right of FIGURE 5c) and produced by battery P (FIGURE 5), (2) a winding carrying a "selection pulse IS" coming from one output (sp) of scanner EX (FIGURE 5) which is an artificial delay line or a magnetic shift register, (3) a winding carrying an "information signal Inf" which, in case of disc D_{bp} or D_{vp} or D_{rp} (FIGURE 5), is one of the components of the hue of the saturated color to be reproduced (hue signals B , V , R , taken from the busbars fed by the corresponding terminals B , V or R , of electronic arrangement PR energized by the received videosignal SV); in case of disc D_{1p} (FIGURE 5) the information signal Inf is 20 the luminance signal L (bands B_3 and B_2 of the video-signal-spectrum, FIGURE 1-a) separated by electric filter F and amplified by tetrode T_1 followed by inverting triode T_2 . As shown on FIGURE 5, the negatively biased grid to tetrode T_1 acts as a gate which opens only 25 if saturation signal S has a positive value sufficient for overcoming said negative bias, that is, only if the part of the televised scene to be reproduced at the considered moment has a saturated color.

In the hole between branches 3 and 4 (FIGURES 5 and 5c) pass: (1) a winding carrying an alternating current CA having unequal positive and negative parts in each period, and (2) another winding U in which said alternating current CA induces: the electric voltage (e) for controlling the birefraction of the ferroelectric body associated to the disc (k_{bp} for disc D_{bp} , k_{vp} for disc D_{vp} , or k_{rp} for disc D_{rp} , FIGURE 5), or, in case of disc D_{1p} (FIGURE 5), the electric voltage (e) for controlling simultaneously the gains of amplifiers a_{bp} , a_{vp} , a_{rp} as a function of the luminance L , only when a 35 very saturated color must be reproduced; in the latter case, the variations of brightness from point to point in a large part of the televised scene having a saturated color are so correctly reproduced on the projection screen at the receiving station. Rectifiers R_{bp} , R_{vp} , R_{rp} (shown 40 on FIGURE 5) are in series with amplifiers a_{bp} , a_{vp} , a_{rp} respectively, in the circuits applying the birefraction, controlling voltages to bodies k_{bp} , k_{vp} or k_{rp} and rectifier R_{1p} is in the circuit (of FIGURE 5) for controlling 45 the gains of amplifiers a_{bp} , a_{vp} , a_{rp} as mentioned above. In parallel with the modulating electrodes of ferroelectric bodies k_{bp} , k_{vp} , k_{rp} are diodes (d_{bp} , d_{vp} , d_{rp}) for stopping, at the right time, the birefraction of said bodies, 50 as they constitute (between their respective electrodes) capacitors which must be discharged before receiving another electric charge.

In the central hole of each ferrite disk, there is a winding carrying a "clearing pulse (I_1)" which (at the end of each scanning line) suppresses the effect of negative bias (CC) together with the "marking" of the ferrite disk produced simultaneously by the selection winding (IS) and the information winding (Inf).

FIGURE 5c, at the right, shows the characteristic of such ferrite disks, the abscissa being the number (n) of ampere-turns produced by either of these windings (IS or Inf) and the ordinate being the "set flux" $f = f_{set}$, expressed in volt-microsecond. The ampere-turns (produced by either IS winding or Inf winding) would be inadequate to overcome the negative bias (CC), whereas their sum brings the operating point into the linear part 65 of the characteristic, at a level corresponding to the amplitude of the information pulse (Inf); the "marking" so carried out at this level persists up to the application of the clearing pulse (I_1), because the magnetic circuit through branches 1 and 2 of the disk "protects" 70 the magnetic flux in the circuit through branches 3 and 4.

The scanner EX takes the positive selection pulse (IS), which is the received negative line synchronizing pulse (t_1) inverted and amplified by triode T_0 (FIGURE 5). Since it is desired that each "utilisation circuit" (such as u_{bp}) should operate through the duration T of a scanning line, use is made, to produce the clearing pulse (I_1), of a second scanner EX' (for example another magnetic shift register) which carries a positive pulse produced by the negative line synchronizing pulse (t_1) through a "delaying device (DR)" and an amplifier Am . This local delayer (DR), shown on FIGURE 5d, is a series set-up consisting of an univibrator (uv) having a capacitor C and a resistor R which determine the desired duration (T) of a rectangular output pulse, a deriving circuit (der) having series capacitor and parallel resistor, 15 an amplifier (a), and finally a rectifier (r).

The alternating current CA (FIGURE 5) is produced by the sine-wave-generator O associated with a germanium diode D having a non-linear characteristic; an appropriate amplitude threshold being produced by capacitor C and resistor R in parallel, a wave having unequal positive and negative parts is obtained at the output, and feeds the busbar labelled CA on FIGURE 5.

As shown on FIGURES 5 and 5a, for each element of a line of the coarse colored picture to be produced on projection screen EP, there is a "control chain" with 4 ferrite disks (such as D_{bp} , D_{vp} , D_{rp} and D_{1p}) and three transparent ferroelectric bodies (such as k_{bp} , k_{vp} and k_{rp} with their associated color filters f_{bp} , f_{vp} , f_{rp}) the electrodes of which are submitted to electric voltages modulating the color of the light emerging from final lens (such as l_{2p}); these various control chains are juxtaposed along the line of electric sources of white light (188 lamps such as σ_p , for U.S. color television standards). The length of the whole is a few meters, i.e. the width of a large projection screen.

While the invention has been illustrated and described as hereabove, it is not intended to be limited to the details shown, since various modifications and structural changes may be made without departing in any way from the spirit of the present invention.

What is claimed as new and desired to be secured by Letters Patent is:

1. Color television receiver of the type having a projection screen on which are superimposed a detailed black-and-white picture of the televised scene produced by a first projector controlled by a luminance-weighted-signal, and a coarse picture, in saturated colors, of said scene produced by a second projector using transparent bodies becoming birefracting in proportion to color signals characterizing the components of the hue of the color to be reproduced on said screen, comprising:

a device for producing said luminance-weighted-signal which controls said first projector, made of a high-gain-amplifier energized by the received luminance signal and of an electronic multiplier controlled both by the output voltage of said amplifier and by a sat-

uration-signal derived from the received chrominance signal, said multiplier applying a feed-back-voltage to the input of said amplifier;

and comprising, within said second projector, for each colored element of one line of the televised scene:

a small source of parallel rays of polarized white light; one particular group of three transparent crystals juxtaposed with the same orientation of their axes and exposed to said parallel rays, said color signals controlling electric fields applied to said three crystals; a color filter having juxtaposed elements of saturated blue, green and red colors, respectively in line with said three juxtaposed crystals; a group of ferrite discs acting as electronic memory for keeping the intensities of said electric fields applied to said crystals constant during the whole scanning of said line of the televised scene; an analyser located beyond said color filter and transverse to the direction of polarization of said parallel rays;

and a lens located beyond said analyser, for focussing the colored light emerging from said analyser upon the part of said projection screen corresponding to said colored element of said line of the televised scene,

whereby there are produced, on said screen, juxtaposed colored picture elements each having the same saturated color on its entire surface, and forming together said coarse picture, in saturated colors, of the televised scene.

2. Color television receiver in accordance with claim 1, in which said electronic multiplier, within said device producing said luminance weighted signal, is an heptode having two control-grids respectively energized by the output-voltage of said high-gain-amplifier and by said saturation signal proportional to the degree of saturation of the color to be reproduced on said projection screen.

3. Color television receiver in accordance with claim 1, in which said electronic multiplier, within said device producing said luminance weighted signal comprises in combination:

an electronic adder and an electronic subtracter to which are simultaneously applied the output-voltage of said high-gain-amplifier, and said saturation signal proportional to the degree of saturation of the color to be reproduced on said projection screen; two non-linear-amplifiers respectively energized by said adder and by said subtracter; and another electronic subtracter energized by said two non-linear-amplifiers simultaneously, the output voltage of said other subtracter being applied, as feed-back, to the input terminal of said high-gain-amplifier.
